DESIGN FOR A PHONOGRAPH TONE ARM

Carl W. D. Schaefer, Dayton, Ohio, assignor to
Phileo Corporation, Philadelphia, Pa., a cor-
poration of Pennsylvania

Application September 29, 1948, Serial No. 148,873

Term of patent 7 years

(Cl. D26—14)

To all whom it may concern:

Be it known that I, Carl W. D. Schaefer, a citizen of the United States, residing at Dayton, in the county of Montgomery and State of Ohio, have invented a new, original, and ornamental Design for a Phonograph Tone Arm, of which the following is a specification, reference being had to the accompanying drawing, forming part thereof, in which:

Figure 1 is a plan view of a phonograph tone arm, embodying my novel design;

Figure 2 is a side elevational view;

Figure 3 is a side elevational view;

Figure 4 is an end elevational view, looking in the direction of arrows 4—4 in Figure 3; and

Figure 5 is a sectional view taken at line 5—5 of Figure 2.

I claim:

The ornamental design for a phonograph tone arm, substantially as shown.

CARL W. D. SCHAEFER.
